UNITED STATES PATENT OFFICE

DONALD S. BARROWS, OF ROCHESTER, NEW YORK, ASSIGNOR TO THE GOULD COUPLER COMPANY, OF DEPEW, NEW YORK, A CORPORATION OF MARYLAND

SIDE FRAME

Application filed April 18, 1928. Serial No. 270,922.

This invention relates to side frames for railway trucks and more particularly to the reinforcement of the connection between the ends of such frames and journal boxes 5 formed integral therewith.

The principal object of my invention, generally considered, is the reinforcement of the union between integral journal boxes and the adjacent ends of cast side frames for railway 10 car trucks.

Another object of my invention is the strengthening of the junction between integral journal boxes formed at the ends of side frames for railway car trucks by reinforcing 15 the lower web of the tension member of such side frames and extending such reinforcement beyond the junctions with the journal boxes, and along the roofs thereof.

A further object of my invention is the 20 rigidifying of the end construction of cast side frames with integral journal boxes and particularly of such side frames in which the tension and compression members are generally U and inverted U-shape in cross section 25 by providing upstanding ribs extending approximately along the longitudinal center line of the web of the tension member and continued past the junction with the journal boxes over the roofs of said boxes.

A still further object of my invention is to 30 provide a special reinforcement adjacent the junctions between integral journal boxes and the ends of cast side frames, said side frame preferably comprising a tension member 35 formed with a lower web and upstanding side flanges, said web being united with the journal boxes adjacent the upper corners of the inner brass lugs thereof, the junctions being reinforced by upstanding ribs preferably 40 beaded along their upper edges and tapering longitudinally both ways from the junctions with the journal boxes along the web of the tension member and the roofs of said boxes, 45 the outer ends of said ribs preferably merging with ribs extending along the transverse center line of the boxes and connecting the side walls of the frame, the junctions with said boxes being preferably additionally reinforced by beaded gussets between the inner 50

side walls of the boxes and the underside of the tension member.

Referring to the drawings illustrating my invention, the scope whereof is defined by the appended claims:

55

Figure 1 is a plan of one end of cast side frame for railway car trucks, a portion thereof being shown in section.

Figure 2 is a fragmentary vertical longitudinal sectional view of the frame illustrated 60 in Figure 1.

Figure 3 is a transverse sectional view on the line 3—3 of Figure 2, looking in the direction of the arrows.

Figure 4 is a sectional view corresponding 65 to Figure 2 but showing a modification.

Figure 5 is a transverse sectional view on the line 5—5 of Figure 4, looking in the direction of the arrows.

Figure 6 is a sectional view corresponding 70 to that on the line 6—6 of Figure 4 but showing another modification.

Referring to the drawings in detail, like parts being designated by like reference characters, and first considering the embodiment of my invention illustrated in Figures 1, 2 and 3, there is shown one end of a cast side frame 1 formed with a compression member 2, a tension member 3, and integral journal boxes 4, only one of which is illustrated. 80 As will be understood, the frame is symmetrical and is formed as usual with the compression member and tension member extending substantially the full length thereof and integrally united at the ends to each 85 other and to the journal boxes, the intermediate portions of said compression and tension members being spaced by bolster guide columns or strut portions, not shown. Inasmuch as certain of the aforementioned 90 features are usual and well known and are not part of my invention, they are not illustrated.

In the present embodiment of my invention the compression and tension members 95 are respectively inverted U and U-shaped in cross section, said compression member being formed with an upper web 5 and depending flanges 6 preferably beaded, as indicated at 7, along their lower edges. The tension mem- 100

ber comprises a lower web 8 and upstanding flanges 9 preferably beaded along their upper edges, as indicated at 10. The flanges 6 and 9 of the members extend toward each other and merge adjacent the ends of the frame forming the sides thereof and continue over the roof 11 of each journal box 4, the outer ends of said flanges preferably curving downwardly, as indicated at 12, to aline and merge with the upper edge of the outer side wall of the journal box. The web 5 of the compression member if desirably discontinued short of any union with the journal box to effect a saving in weight and facilitate

10 core removal.

15

The journal box is not only connected to the frame by having the flanges of the members, after mergence, integrally united to the roof thereof but the web 8 of the tension member is united directly with the roof of the box along the inner edge thereof or upper edge of the adjacent side wall and more specifically preferably in line with the inner brass lug 13 of said box. Adjacent the 20 union with the roof of the box the web of said tension member is preferably slightly thickened, as indicated at 14. The strength of connection with said box is desirably additionally reinforced by providing outstanding gussets 15 preferably formed as flared extensions from the web of the tension member.

25

For additionally reinforcing the connection with the journal box a longitudinally extending rib 16 is preferably provided along the longitudinal center line of the tension member web 8 and frame, said rib preferably being of greater strength directly over the junction between the box and web 30 of the tension member and tapering both ways from said junction so as to gradually merge into the web of the tension member at one end and into a transverse reinforcing web 17 extending upwardly from the roof 35 of the box 4 between the side walls of the frame and preferably tapering from each side wall to the union with the rib 16. The upper edge of said rib is preferably beaded along its intermediate portion, as indicated 40 at 18, giving said rib a T-shape in cross section. Said beading preferably tapers both ways from a point nearest the junction between the tension member and box so that the ends of the rib 16 are free from the beading 45 at 18. This construction provides for maximum economy in the use of the reinforcing metal. For further strengthening the connection between the box 4 and the frame, the inner side wall 19 of said box is preferably 50 directly united to the undersurface of the tension member 3 by a strut or tie member 20, the upper edge of which is preferably spaced from the corner between the web of the tension member and the box and both edges are preferably beaded or flanged, as

indicated at 21, for improving the strength of said member.

Referring now to the embodiment of my invention illustrated in Figures 4 and 5, a construction is there disclosed involving a frame 1^a having the tension member 3^a, the compression member 2^a, and the integral journal box 4^a at each end thereof. As in the previous embodiment, the compression and tension members are respectively generally inverted U and U-shaped in section and the web 8^a of the tension member unites integrally with the roof and inner side wall of the journal box, preferably at the upper end of the inner brass lug 13^a. As in the previous embodiment, the junction between the web 8^a of the tension member and the roof 11^a of the inner side wall 19^a of the box is reinforced by a longitudinally extending rib 16^a which, in the present embodiment, is plain, that is not provided with a beaded upper edge but tapers both ways from the junction between the web 8^a and the journal box. The outer end, however, instead of stopping at the transverse reinforcing web 17^a, preferably continues beyond the said web to finally merge into the roof of the journal box at the outer brass lug 22.

70

75

80

85

90

95

In the present embodiment the inner side wall 19^a of the box is integrally connected to the underside of the tension member web 8^a by a gusset 20^a, the lower edge of which is preferably beaded, as indicated at 21^a, which gusset entirely closes the angle beneath the web of the tension member and inwardly of the inner side wall of the journal box. Except as specifically described in connection with the present embodiment, the construction thereof may correspond with that of the first embodiment.

100

105

Referring now to the embodiment of my invention illustrated in Figure 6, a construction is there disclosed which may be identical with the embodiment illustrated in Figures 4 and 5 except that the web of the tension member and the roof 11^b of the journal box 4^b are provided with a plurality of reinforcing ribs 16^b which extend over the junction between the web of the tension member and the roof of the journal box and taper both ways therefrom. As in the previous embodiment, the ribs 16^b merge into the transverse reinforcing web 17^b between the sides of the frame along the transverse center line of the box. Otherwise the construction of the present embodiment may correspond with that of the previous embodiment.

110

115

120

From the foregoing description it will be appreciated that I have provided means for efficiently improving the strength of the connection between the ends of a side frame and associated integral journal boxes. The proposed reinforcements were devised to overcome weaknesses at the junctions between such frames and journal boxes which

125

130

heretofore became evident by the development of cracks at such points when frames unprovided with my reinforcements were tested.

5 Having thus described my invention, I claim:

1. A truck side frame comprising a compression member, a tension member, said members having webs and flanges extending toward each other from the sides of said webs, journal boxes integrally connected to the ends of the frame, the web of the tension member joining the roof of each journal box at approximately the upper edge of the adjacent side wall lug and reinforced adjacent said junction by a longitudinal upright rib terminating short of the web of the compression member.

2. A truck side frame comprising a tension member, a compression member, said members being respectively **U** and inverted **U**-shape in cross section with the flanges of said members merging adjacent the ends thereof, journal boxes at the ends of the frame, the web of the tension member joining each journal box roof at the adjacent edges thereof and reinforced adjacent said junctions by longitudinal upright ribs extending from a substantial distance below the junctions with the journal boxes, continuing beyond said junctions for a substantial distance over the roofs of the journal boxes, and terminating below the web of the compression member.

3. A truck side frame comprising a tension member, a compression member, said members being respectively **U** and inverted **U**-shape in cross section with the flanges thereof merging adjacent the ends, journal boxes integral with the ends of the frame, the web of the tension member joining each journal box at approximately the upper edge of the inner side thereof and reinforced adjacent said junction by a longitudinal upstanding rib disposed along the longitudinal center line of the frame and of less height than the distance between the web of the compression member and the roof of the box.

4. A truck side frame comprising a tension member, a compression member, said members being respectively **U** and inverted **U**-shape in cross section, journal boxes integral with the ends of said frame, the lower web of the tension member joining each box at approximately the upper corner of the inner brass lug and reinforced adjacent each junction by a longitudinal beaded rib extending from below the junction along the roof of the journal box and formed of maximum strength adjacent said junction.

5. A truck side frame comprising a tension member, a compression member, said members having webs and flanges on the edges thereof extending toward each other and merging adjacent the ends of said frame, journal boxes at the ends of the frame, the

lower web of the tension member joining each journal box at approximately the upper corner of the inner brass lug and reinforced adjacent the junctions by longitudinal ribs flanged along their upper edges and gradually tapering both ways from said junction to merge into the web of the tension member and the roofs of the journal boxes.

6. A truck side frame comprising a tension member, a compression member, said members being respectively generally **U** and inverted **U**-shape in section, journal boxes at the ends of the frame, the lower web of the tension member joining each journal box at approximately the upper corner of the inner brass lug and reinforced adjacent said junction by a longitudinal rib which extends from the web of the tension member, gradually increases in height to a maximum over the junction with the journal box and decreases in height along the roof of the journal box, the end of said rib merging into a transverse rib extending from the roof of the journal box between the side walls of the frame.

7. A truck side frame comprising a tension member, a compression member, said members being respectively generally **U** and inverted **U**-shape in cross section, journal boxes at the ends of the frame, the lower web of the tension member joining each journal box adjacent the upper edge of the inner side thereof, the junction with each box being reinforced by a tapering rib extending upwardly from the web of the tension member over the junction and along the roof of the box, and a gusset extending downwardly from the web of the tension member and uniting with the inner side wall of the box.

8. A truck side frame comprising a tension member, a compression member, said members being respectively generally **U** and inverted **U**-shape in cross section, journal boxes at the ends of the frame, the lower web of the tension member intersecting and joining each journal box and reinforced by local upstanding ribs at the ends of said web terminating beneath the top portion of the compression member.

9. A truck side frame comprising a tension member, a compression member, said members involving webs and flanges extending toward each other and merging adjacent the ends of the frame, journal boxes integrally connected to the ends of said frame, and reinforcing means at the junctions between the journal boxes and frame, said means comprising gussets extending from the lower surface of the web of the tension member to the side walls of the boxes, and upstanding **T**-shaped ribs extending over the junctions between the web of the tension member and the journal boxes.

10. A truck side frame comprising a tension member formed with a lower web, journal boxes at the ends of the frame, said lower

web meeting and integrally connecting with each journal box and reinforced by a rib with a free upper edge and extending upwardly from the web of the tension member over the 5 junction with each journal box and along the roof of said box.

11. A truck side frame comprising a tension member formed generally U-shaped in cross section, a journal box at the end thereof 10 joined with the lower web thereof, the junction with said journal box being reinforced by an upstanding rib tapering both ways from a maximum adjacent said junction.

12. A truck side frame comprising a tension member formed with a web and upstanding flanges at the sides thereof, a journal box integrally connected with the web of said tension member, the junction with said box being reinforced by an upstanding rib extending 20 along the longitudinal center line of the frame and beaded along its upper edge adjacent the junction between the tension member and box, the connection between said member and box being additionally strengthened 25 by a beaded gusset between the inner side wall of the box and the underside of said tension member.

13. A truck side frame comprising a tension member formed with a web and upstanding flanges at the sides thereof, a journal box 30 at an end of said member, the web of said member integrally uniting with the roof of said journal box adjacent the junction with the inner side wall thereof, the flanges continued 35 over the roof of said box, and reinforcing means at the junction between said member and box comprising a gusset disposed along the longitudinal center line of the frame in the angle between the lower side of 40 the tension member and the inner side wall of the box, said gusset being beaded along the lower edge thereof and extending in an approximately horizontal direction from the lower end of the inner brass lug to the under- 45 side of the tension member.

In testimony whereof I affix my signature.
DONALD S. BARROWS.
